UNITED STATES PATENT OFFICE.

CLARENCE E. GREELY, OF ST. PAUL, INDIANA.

CONVEYER-BUCKET.

1,171,516.

Specification of Letters Patent. Patented Feb. 15, 1916.

Application filed February 20, 1915. Serial No. 8,737.

To all whom it may concern:

Be it known that I, CLARENCE E. GREELY, a citizen of the United States, residing at St. Paul, Decatur county, and State of Indiana, have invented and discovered certain new and useful Improvements in Conveyer-Buckets, of which the following is a specification.

My invention relates to buckets for elevating conveyers and its object is to provide effective means for preventing material such as stone or rocks falling from the bucket upon the belt and crowding between such bucket and the surface of the belt or beneath the bucket and particularly to thus protect the belt and bucket when the latter is passing over the pulley of the conveyer.

With this object in view, my invention is embodied in preferable form in the construction hereinafter described and illustrated in the accompanying drawings.

In these drawings, Figure 1 is a side view in elevation of an elevating conveyer showing buckets embodying my invention applied thereto; Fig. 2, an enlarged plan view of one of the buckets; Fig. 3, an enlarged vertical section.

Referring to the drawings, 1 designates a conveyer belt which is adapted to be so mounted as to carry material from one point to a more elevated point and which is driven by and passes around an upper pulley 2 and a lower pulley 3. Secured on this belt by rivets or other suitable means of connection are conveyer buckets 4 having their lower or bottom ends, viewed in the line of flight of the conveyer, provided with a retaining flange and being open at their upper or forward ends for the purpose of permitting the material to be discharged as the bucket reaches the upper pulley and descends on the downward stretch of the belt.

Adapted to be secured to this bucket by rivets or other suitable means of fastening is a plate 5 bearing against the bottom of the bucket. This plate is secured on the upper face of the bottom of the bucket and projects forwardly beyond the edge of the bucket proper a short distance and at the forward projecting edge is provided with ears 7 turned over so as to form alternate receiving sockets for the pintle of a hinge.

An apron 8 is hinged to this plate and extends forwardly along the belt. The rear edge of this apron is provided with ears 9 similar to the ears 7 and through the ears of the belt and apron respectively is adapted to be passed a pintle 10. By means of this hinge connection the apron is loosely connected to the forward portion of the bucket. The apron is extended beyond the sides of the bucket at each end thereof for the purpose of preventing the apron from falling within the body of the bucket as the latter is moved upwardly.

The width of the apron is such in relation to the distance between two adjacent buckets that as the apron falls downwardly toward the belt as the buckets are passing over the pulley, the forward edge of the apron will strike against the rear wall of the preceding bucket and rest against the same at an angle, thus effectually preventing stones or other material carried by the bucket from falling therefrom down upon the belt or becoming lodged between the belt and preceding bucket or between the apron and said bucket, or between the belt and the bucket carrying the apron.

If desired, the hinge members such as 5, 80 may be formed directly upon the forward edge of the bottom of the bucket and the apron thus hinged directly to the bucket body, but the use of the attached plate carrying the hinge renders the device capable 85 of application to buckets already in use.

Having thus described my invention, what I claim is:

1. A conveyer having a belt and a series of conveyer buckets, in combination with an apron between each two adjacent buckets, said apron being hinged to the forward bucket and extending above the bottom line of the buckets at an angle to the belt and over the space between said buckets so as 80 to lie against the wall of the preceding bucket above the bottom thereof whenever the buckets are traveling at such an angle as to cause the apron to swing forwardly.

2. A conveyer bucket closed at one end 10 and open at the forward end in the line of travel for the purpose of permitting the discharge of material, in combination with a plate attached to said bucket, an apron ex-

tending forwardly from said bucket and adapted to occupy the space between the two adjacent buckets above the bottom line of the buckets and hinged members connecting 5 said apron and said plate.

In witness whereof, I have hereunto set my hand and seal at Indianapolis, Indiana,

Copies of this patent may be obtained for five cents each, by addressing the "Commissioner of Patents, Washington, D. C."

this seventeenth day of February, A. D. nineteen hundred and fifteen.

CLARENCE E. GREELY. [L. S.]
